DISPLAY COPIER FOR DATA PROCESSING SYSTEMS OR THE LIKE

William S. Sheppley, Jr., Rhinebeck, N.Y., assignor to
International Business Machines Corporation, Armonk,
N.Y., a corporation of New York

Filed Feb. 26, 1968, Ser. No. 10,707

Term of patent 14 years

U.S. Cl. D61—1
Int. Cl. D14—02

FIG. 1

FIG. 2

FIG. 3

FIG. 1 is a front, top and right side perspective view of a display copier for data processing systems or the like showing my new design;

FIG. 2 is a left side elevational view; the right side being substantially a mirror image thereof; and

FIG. 3 is a rear elevational view thereof.

I claim:

The ornamental design for a display copier for data processing systems or the like, substantially as shown and described.
